SHEET FOLDING MECHANISM

Application filed September 2, 1931. Serial No. 560,772.

This invention relates to a folding mechanism adapted to fold a sheet of indefinite length back and forth into a series of plaits without pinching the sheet at any of the creases or unduly pressing the material of the sheet at any point. In the manufacture of nitrated cellulose it has been found advantageous to prepare cellulose for nitration by the manufacture of pure alpha fiber from wood pulp, this fiber being formed into sheets which are porous and loosely felted and which are commonly known as "web stock." Such sheets may be suspended in suitable nitrating acid for nitration. The sheet readily absorbs the acid and the nitration proceeds to completion uniformly over the sheet if there are no disturbing factors. Since, however, the chemical reaction of nitration is attended with the release of a certain amount of heat, and since the rate of the nitrating reaction varies with the temperature, it is necessary to maintain free circulation of the acid over the surfaces of the sheet to avoid local accumulation of heat on one or more portions of the sheet, with resulting rise in local temperatures and uneven nitration. For this reason it is necessary that contact of the sheet with the sides of the container for the bath, or with other sheets, be avoided or at least reduced to areas of negligible size.

If plane sheets of web stock be suspended side by side in the nitrating bath, the tendency of the sheets to warp and bend in the acid results in a liability of the sheets to come into contact over substantial areas with each other or with the container itself. Such contact areas confine the heat of chemical reaction locally and result in a "burning" of the contacting sheets over these areas due to excessive nitration caused by the local increase in temperature. In order to overcome this difficulty, the sheets may be plaited by folding back and forth, the plaits in each sheet suspended in the bath being arranged at an angle to the plaits of the next adjacent sheets, so that the areas of contact between adjacent sheets are negligibly small and are insufficient to prevent the free circulation of acid between the sheets to carry off heat generated by the nitrating reaction.

It is also important that the material of the sheet itself be of substantial uniform density. If portions of the sheet are compressed in handling, the penetration of the nitrating acid is not as thorough or rapid as in the more loosely felted portions of the sheet so that at such point in the sheet, there is liable to be insufficient nitration. 55

The present invention is more particularly for the purpose of providing apparatus capable of folding a sheet of web stock or the like into a series of plaits without unduly pinching or compressing the material of the sheet so as to render it less absorbent in localized areas. For this purpose mechanism is provided consisting essentially of a pair of folding blades which have overlapping portions, the leading blade being moved clear of the following blade and then swung around behind the following blade so as to come up 60 behind it with a fresh fold in the sheet, the following blade thus becoming the leading blade. This action is repeated alternately by the two blades so that the sheet is successively folded back and forth without 65 pinching the folds and without compressing 70 the sheet. 75

For a more complete understanding of the mechanism by which the invention is carried out, reference may be had to the description 80 thereof which follows and to the drawings, of which, —

Figure 1 is a longitudinal section of a machine embodying the invention taken on the line 1—1 of Figure 3. 85

Figure 2 is a plan view of the portion of the mechanism shown in Figure 1.

Figure 3 is an end elevation of a mechanism embodying the invention.

Figure 4 is a portion of Figure 1 shown 90 on an enlarged scale.

Figure 5 is a fragmentary sectional view of a blade.

Figure 6 is a section on the line 6—6 of Figure 5. 95

The folding mechanism includes a guide-way for the sheet which, as shown, may comprise a series of lower rods or wires 10 and a series of upper rods or wires 11. The lower guide rods 10 may extend from a suitable 100

platform 12 through the machine to terminate at a suitable discharge point 13. The upper guide wires 11 are substantially parallel to the lower wires 10 so that a suitable 5 guiding space is provided for the sheet as it passes through the machine. A pair of folding blades including a lower blade 14 and an upper blade 15 are mounted centrally in the machine and extend thereacross from one 10 side to the other. These blades are automatically operated by mechanism hereinafter described so that each blade moves alternately from a leading position to a following position, the lower blade being within 15 drawn downwardly until its overlapping portion clears the upper blade, then being swung rearwardly and upwardly into a position behind the upper blade, thus forming an additional fold in the sheet which is fed 20 across the platform 12. Similarly, the upper blade is then moved over and behind the lower blade. Since the overlapping portions of the blades 14 and 15 project beyond the adjacent guide rods 11 and 12 into the guiding channel defined by these rods, the blades are suitably notched to receive these guide 25 rods.

The guide channel, the folding blades, and the mechanism for operating the folding 30 blades are all carried on a suitable frame 20. This frame may include a platform 21 to support an electric motor 22, belt pulley, or other driving means. The motor is connected by suitable reducing gearing 23 to a 35 sprocket wheel 24 which is mounted on a shaft 25. Mounted on the shaft 25 is a pair of disks 26, 26 which are similar in structure, each of these disks having a suitable cam slot 27 therein. As shown in Figure 1, 40 this slot may consist of a channel in the face of each disk, the channel being circular for about 270° and being reentrant, as at 28, through the remaining 90°. A cam follower 30, which may be a suitable roller, rides with- 45 in each slot 27, each of the cam followers 30 being mounted on a horizontal bar 31 which is reciprocable in suitable bearings carried by the frame 20. Mounted on each bar 31 is a vertical cross-head 32 which 50 is grooved as at 33 to receive a roller 34 for reciprocation therein. Each roller 34, as indicated in Figure 3, is mounted at the lower end of an arm 35 which extends downwardly 55 from a carrier 36, the carrier being adapted to rock on the axis of a pin 37 which projects through a vertical slot in a frame member 38, the end of the pin 37 being provided with a roller 39 which rides in a cam slot 40. The carriers 36 receive loosely the opposite ends 60 of the lower blade 14, as indicated in Figure 4, each carrier having a pair of side walls spaced to permit limited rocking movement of the blade therein. A suitable spring 41 is provided within each carrier to press 65 the blade 14 resiliently against the rear walls

of the carriers 36. The blade 14 is provided with a pair of hinged members 43 which are connected to the carriers as by hinged pins 44 extending through suitable gears in the hinged members 43 and the carriers 36. 70 Thus the blade is reciprocable on the pins 44, the rocking motion being limited by the walls of the carrier 36.

Similar apparatus is provided for the operation of the upper blade 15. To this end 75 a pair of gears 45 may be mounted on the shaft 25 near the ends thereof, the gears 45 meshing respectively with a pair of idle gears 46 which, in turn, mesh with horizontal gears 47 mounted on vertical shafts 48 at their lower ends. On the upper ends of these shafts are respectively mounted a pair of gears 51. The gears 51 mesh with idle gears 52 which, in turn, mesh with a pair of gears 53 mounted 80 on a shaft 54. The shaft 54 carries a pair of cam disks 55 which are identical in structure with the cam disks 26, hereinbefore described. The disks 55 are provided with cam grooves 56 identical with the grooves 27. Cam followers 57 ride in the grooves 56 and are 85 mounted on horizontal reciprocating bars 58. These bars each have a central cross-head 60 which is slotted at 61, suitable rollers 62 being vertically reciprocable in these slots. The rollers 62 are mounted on a pair of carriers 63 similar to the carriers 36, the upper blade 15 having a pair of hinged members 64 which are connected to the carrier 63 as by hinged pins 65, the structure being substantially 90 identical with the supporting members for the lower blade 14, hereinbefore described in detail. The upper carriers 63 are mounted for rocking motion about the axis of a pin 70 which projects through a vertical slot in the frame member 38, the remote end of the pin 70 having roller 71 which rides in a cam slot 72 similar to the cam slot 40. On each of the shafts 48 is mounted a vertical cam drum 73, each drum having a slot 40 and a slot 72 in its cylindrical wall. Each of 95 these cam slots extends horizontally around the periphery of the drum for about 180°. Through 90° each slot swings toward the adjacent end of the drum, and then back through the remaining 90° to its horizontal 100 portion, as indicated in Figure 4.

The blades 14 and 15 each present a blunt edge 80 to the sheet. These blades may also carry auxiliary pricking blades 81 having sharp serrated edges 82 to pierce the sheet at the folds in series of small cuts which facilitate creasing the sheet with a minimum of creasing pressure. The blades 81 are slidably mounted in slots in the body portions of the blades 14 and 15 respectively. Secured 110 to the back edge of each of the blades 81 are a pair of bolts 83 which project through suitable holes 84 in the carriers 36 and 63. The holes 84 are large enough to contain a compression spring 85 around each bolt. These 115

5 springs tend to retract the pricking blades 81 and to maintain the serrated edges 82 in inoperative position back of the blunt edges 80. To render the blades 81 operative the blades 14 and 15 are notched as at 86 to receive levers 7 which are pivoted by pins 88 to ears 89 projecting from the blades 14 and 15. These levers project out from the carriers 36 and 63 and reciprocate therewith. In the path 10 of motion of the free ends of these levers are trip-pins 90 which are mounted on brackets 91 secured to the main frame. When the blade 14 or 15 approaches the end of its stroke, the corresponding levers 87 strike their trip-pins 90 and rock on their pivots 88, projecting the pricking blade 81 so that its serrated cutting edge 82 projects beyond the adjacent blunt edge of the blade 14 or 15.

15 The operation of the mechanism is as follows: Starting with the lower blade 14 in the leading position, as shown in Figure 1, the rotation of the cam drums 73 results in a downward movement of the blade 14 as the cam follower 39 rides into the descending portion of the cam slot 40. This moves the blade 14 entirely clear of the blade 15. When the blade reaches its lowermost point, the reentrant portion 28 of the cam slot 27 in each cam disk 26 moves the horizontal bars 31 toward the right.

20 This carries the rollers 34 to the right, since these rollers always ride in the grooves 33. The motion of the rollers 34 rocks the carriers 36 and hence the blade 14 on the pins 37 as an axis, this rocking movement being indicated in dotted lines in Figure 4. As soon as the bars 31 reach their extreme position toward the right, they are immediately reciprocated back again to their normal position, the back and forth motion being completed during a quarter turn of the cam disk 26. During this single reciprocation of the bars 31 to the right and back again to the left, the rollers 39 ride in the ascending portions of the cam slots 40 which are shaped in such a manner that the rollers 34 describe a semi-circle, as indicated in Figure 4. This movement swings the upper edge of the blade 14 around behind the blade 15 so that a bight of the sheet is picked up behind the blade 15 and moved up against the rear face of the blade 15. During the final portion of this movement, the levers 87 which are mounted on the blade 14 engage their trip-pins 90 and force the lower pricking blade 81 upwardly to prick a line of short cuts in the sheet. As this motion of the lower blade is completed, the upper blade is pressed slightly forward against its spring 41 to a position equivalent to that in which the blade 14 is shown in Figure 4. The motion described for the blade 14 is now duplicated by the blade 15 as actuated by the several cam followers working in the cam slots 56 and 72.

25 As the motion of this blade is identical with

that of the blade 14, the detailed description thereof is not repeated herein. The pricking blades 81 are not essential to the operation of the apparatus, and may be omitted if desired.

75 The folds of the sheet are thus made in such a manner that the creases are not pinched, nor is there any localized or excessive pressure brought to bear on any portion of the sheet in the course of folding. The plaits of the folded sheet are collected in the guide channel between the bars 10 and 11. This guide channel may be provided with an upwardly sloping portion as at 80 to provide a suitable resistance against which the folding blades may push newly formed folds. As shown the guiding channel may then bend downwardly to its discharge end 13.

80 We claim:

1. Mechanism of the class described comprising a pair of blades having overlapping portions, and means for moving said blades alternately to move the leading blade clear of the other blade and to bring it against the rear face of said other blade.

85 2. Mechanism of the class described comprising spaced guiding members for folded paper, a pair of blades having portions projecting substantially across the space between said members from opposite directions, and means alternately moving said blades to withdraw the leading blade clear of the other and to project said withdrawn blade across said space behind said other blade.

90 3. Sheet folding mechanism comprising a pair of blades having overlapping portions, and means for alternately moving said blades from the leading position to the following position, said means including mechanism for reciprocating each blade alternately in its own plane to clear the other blade and then to move back into overlapping relation, and mechanism for rocking each blade rearwardly when moved clear of the other.

95 4. Sheet folding mechanism comprising spaced guides for a folded sheet, a pair of blades projecting substantially across the space between said guides from opposite directions and overlapping within said space, means for alternately withdrawing from said space each blade when it is leading and for reinserting said blade in said space behind the other blade, said means including a reciprocable slide, a cross-head mounted on said slide and provided with a guide slot perpendicular to said slide, a carrier for the blade having a follower riding in said slot and a second follower spaced from the first, means acting on said second follower to reciprocate said blade substantially in its plane and means for reciprocating said slide to rock said blade.

100 5. Sheet folding mechanism comprising a pair of blades having overlapping portions, means for withdrawing the leading blade to

- clear the other blade and for swinging said leading blade in behind the other blade whereby the blades again overlap with said other blade leading, said means including a blade carrier pivotally mounted to rock said blade and reciprocable substantially in the plane of the blade, cam means for reciprocating said blade carrier, other cam means for rocking said carrier, and common driving means for both said cam means.
- 10 6. Sheet folding mechanism comprising a pair of blades having overlapping portions, means for withdrawing the leading blade to clear the other blade and for swinging said leading blade in behind said other blade whereby the blades again overlap with said other blade leading, said means including a blade carrier on which the blade is mounted for limited rocking movement, a spring on said carrier pressing said blade rearwardly, cam means for reciprocating said carrier and blade substantially in the plane of the blade, other cam means for rocking said carrier and blade, and common driving means for both said cam means.
- 15 7. Sheet folding mechanism comprising a pair of folding blades having overlapping portions, means for moving said blades alternately to move the leading blade clear of the other blade and to bring it against the rear face of said other blade, an auxiliary pricking blade carried by each of said folding blades, and means for operating each said pricking blade when its respective folding blade is completing a folding movement.
- 20 35 In testimony whereof we have affixed our signatures.
